UNITED STATES PATENT OFFICE.

SAMUEL SIMONOVITZ, OF NEW YORK, N. Y.

WINDOW CONSTRUCTION.

Application filed March 11, 1924, Serial No. 698,427.

To all whom it may concern:

Be it known that I, SAMUEL SIMONOVITZ, a citizen of the United States, and residing at New York, in the county of New York 5 and State of New York, have invented certain new and useful Improvements in Window Constructions, of which the following is a specification, such as will enable those skilled in the art to which it appertains to 10 make and use the same.

This invention relates to window constructions and particularly to improved means for mounting and operating the sashes of a window and further to the provision of 15 means for locking the sashes in different positions of adjustment to prevent the further opening of such sashes; and the object of the invention is to provide a window construction of the class and for the purpose 20 specified in which the sashes are so mounted in the window frame as to permit of the removal of said sashes by simply removing retaining and guiding strips; a still further object being to provide means for balancing 25 the sashes in the window frame and further to the provision of means for locking the separate sashes in closed position or any predetermined positions of adjustment against movement in one direction; a still further 30 object being to provide key members for controlling the locking means of the separate sashes; and with these and other objects in view, the invention consists in a window construction of the class and for the purpose specified, constructed as herein- 35 after described and claimed.

The invention is fully disclosed in the following specification, of which the accompanying drawing forms a part, in which the 40 separate parts of my improvement are designated by suitable reference characters in each of the views, and in which:

Fig. 1 is a side view of a window frame showing parts of the mechanism which I employ and part of the construction being 45 broken away.

Fig. 2 is a section on the line 2—2 of Fig. 1.

Fig. 3 is a partial section on the line 3—3 of Fig. 1 on an enlarged scale.

Fig. 4 is a section on the line 4—4 of Fig. 2 on an enlarged scale; and,

Fig. 5 is a section on the line 5—5 of Fig. 1.

In the drawing I have shown at 10 a window frame construction which may be of

any desired form, said frame being provided with side rails 11 and 12 outwardly of which are chambers 13. Mounted in the frame are top and bottom sashes 14 and 15 retained in position by guide and spacing 60 strips 16, 17 and 18.

The outer faces of the side rails of the sashes 14 and 15 are provided with racks 19 and 20 respectively and substantially centrally of the window frame 10 the rail 11 65 thereof is apertured in line with the racks 19 and 20 of the sashes as shown at 21 and 22, while the rail 12 is similarly apertured as shown at 23 and 24. Gears 25 and 26 are mounted on a shaft 27 within the chamber 70 or space 13 and extend through the apertures 23 and 24 and engage, respectively, the racks 19 and 20 on the sashes 14 and 15. The shaft 27 is mounted in bearings 28 and the mounting of the gears 25 and 26 is preferably such as to provide sufficient tension or friction to enable balancing means for 75 the separate sashes, to be dispensed with.

The rail 11 of the frame is preferably provided with a removable panel 29 held in 80 place by screws 30, and mounted in suitable bearings on the panel 29 are two shafts 31 and 32, the inner or free ends of which are angular in form as shown at 33 and extend through apertures in the inner face of the 85 window frame. Key members 34, preferably provided with knurled heads, are detachably mounted in connection with the angular ends of the shafts 31 and 32, and said key members serve to rotate the 90 separate shafts. Secured to the shaft 31 is a pawl 35 and a pawl 36 is secured to the shaft 32. These pawls are so positioned as to pass through the apertures 21 and 22 in the rail 11 and engage the racks 19 and 20 95 on the sashes. At the outer ends of the shafts 31 and 32 are enlarged disk-shaped members 37 with which springs 38 are connected, said springs being also connected to posts 39 mounted in the panel 29. The 100 mounting of the springs 38 is such that the springs are under greatest tension when the coupling thereof to the disks 37 and to the posts 39 are in common alinement with the axis of the shafts 31 and 32 and by rotating the shafts in one direction the springs will

105 move the pawls 35 and 36 into engagement with the separate racks and retain the same in such position or said springs will hold said pawls in an inoperative position, in ro- 110

tating the shafts in the opposite direction and beyond the dead center.

It will be noted that by removing one of said strips 18 the lower sash 15 may be removed and by removing one of said strips

5 17, the upper panel may be removed and these strips may be secured to the side rails of the window frame by screws or in any other desired manner.

10 With my improved construction, it will be understood that the sashes 14 and 15 may be moved upwardly and downwardly in the window frame at will by moving both of the pawls 35 and 36 into inoperative positions or out of engagement with the racks on said sashes, and if it be desired to lock the sashes in an open position as shown in Fig. 2 said pawls are moved into operative position by means of the keys 34. When the

15 sashes are locked in an open position as shown in Fig. 2, it will be impossible to open the sashes further, but both sashes may be closed without manipulating the pawls 35 or 36. By providing the removable plate 29,

20 the operative mechanism including the shafts 31 and 32, pawls 35 and 36, etc. may be removed for repair or other purposes if ever desired, and the gears 25 and 26 may be similarly mounted if desired, and various

25 changes in and modifications thereof may be made within the scope of the appended claims without departing from the spirit of my invention or sacrificing its advantages.

Having fully described my invention, what

30 I claim as new and desire to secure by Letters Patent, is:

1. A window construction of the class described comprising a sash frame, sashes mounted to move vertically in said frame, strips for retaining said sashes in predetermined position and for guiding the same in their movement and whereby the removal of a predetermined number of said strips will permit of the removal of said sashes, means involving gear and rack constructions for retaining the sashes in predetermined positions of adjustment, manually operated means for locking the separate sashes in predetermined positions, said last named means comprising the racks on said sashes, and pawls pivotally mounted in the frame and cooperating directly with said racks.

2. A window construction of the class described comprising a sash frame, sashes mounted to move vertically in said frame, strips for retaining said sashes in predetermined position and for guiding the same in their movement and whereby the removal of a predetermined number of said strips will permit of the removal of said sashes, means involving gear and rack constructions for retaining the sashes in predetermined positions of adjustment, manually operated means for locking the separate sashes in predetermined positions, said last named means

comprising the racks on said sashes, pawls pivotally mounted in the frame and adapted to cooperate with said racks, and tensional means for moving said pawls into operative and inoperative positions.

3. A window construction of the class described comprising a sash frame, sashes mounted to move vertically in said frame, strips for retaining said sashes in predetermined position and for guiding the same in their movement and whereby the removal of a predetermined number of said strips will permit of the removal of said sashes, means involving gear and rack constructions for retaining the sashes in predetermined positions of adjustment, manually operated means for locking the separate sashes in predetermined positions, said last named means comprising the racks on said sashes, pawls pivotally mounted in the frame and adapted to cooperate with said racks, tensional means for moving said pawls into operative and inoperative positions, and keys for controlling the operation of said pawls.

4. A lock device for window sashes comprising racks secured to one side of the separate sashes, pawls pivotally mounted in position to cooperate with said racks, tensional means for holding said pawls in operative and inoperative positions and means involving a key for manually actuating said pawls.

5. A lock device for window sashes comprising racks secured to one side of the separate sashes, pawls pivotally mounted in position to cooperate with said racks, tensional means for holding said pawls in operative and inoperative positions, means involving a key for manually actuating said pawls, and said pawls and cooperative parts being mounted on a removable section.

6. A window construction of the class described comprising a frame, sashes movably mounted in the frame and removable therefrom, racks on the side rails of said sashes pawls mounted in one side of the frame and cooperating directly with the racks on the adjacent side rails of said sashes and means involving a key for actuating said pawls.

7. A window construction of the class described comprising a frame, sashes movably mounted in the frame and removable therefrom, racks on the side rails of said sashes, pawls mounted in one side of the frame and adapted to cooperate with the racks on the adjacent side rails of said sashes, means involving a key for actuating said pawls, and tensional means controlling the separate pawls for retaining the same in operative and inoperative positions.

8. A window construction of the class described comprising a frame, sashes movably mounted in the frame and removable therefrom, racks on the side rails of said sashes, pawls mounted in one side of the frame and

adapted to cooperate with the racks on the adjacent side rails of said sashes, means involving a key for actuating said pawls, tensional means controlling the separate pawls for retaining the same in operative and inoperative positions, and gears mounted in the other side member of the frame and co-

operating with the racks on the other side rails of said sashes.

In testimony that I claim the foregoing as 10 my invention I have signed my name this 8th day of Mar. 1924.

SAMUEL SIMONOVITZ.
